CARD AND ENVELOPE SUPPORTING TRAY

Elmer M. Wangen, Duluth, Minn.

Application July 25, 1932, Serial No. 624,560

5 Claims. (Cl. 211—11)

The invention relates to an adjustable tray for use with typewriters so that envelopes, cards and the like can be supported upright and located in the most accessible position.

5 An object of the invention is to provide a card and envelope supporting tray which can be adjusted vertically as well as horizontally and which can be swung out of position when not in use. The spaced uprights for holding the cards and 10 envelopes are also relatively adjustable so that the capacity of the tray can be varied within limits.

A further object is to provide a device for the purposes described which will be independent of 15 the typewriter and which can be located in the most accessible position when in use, allowing folding of the typewriter desk by merely setting the device to one side out of the way.

With these and various other objects in view, 20 the invention may consist of certain novel features of construction and operation, as will be more fully described and particularly pointed out in the specification, drawing and claims appended hereto.

25 In the drawing which illustrates an embodiment of the device and wherein like reference characters are used to designate like parts—

Figure 1 is an elevational view of the card and envelope supporting tray with the base of the 30 standard being shown in section;

Figure 2 is a front elevational view of the device;

Figure 3 is a plan view of the device showing the constructional features by which the tray is 35 adjustable for size and adjustably secured to its support;

Figure 4 is a fragmentary sectional view taken on line 4—4 of Figure 3; and

Figure 5 is a sectional view taken on line 5—5 40 of Figure 3;

Referring to Figures 1 to 5 inclusive the supporting tray of the present invention is shown as including a standard 10 having a base 11 provided with a recessed portion 12 in its upper surface for receiving clips, pins, etc., the standard 45 positioning vertically in adjusted position, by means of the collar 13, a horizontal member forming the support 14 having side frame members 15 which taper toward each other at one end for 50 retaining the spool 16 serving to rotatably mount the support on the standard 10. The upper surface of the support has a member 17 provided with upstanding marginal flanges either formed 55 integrally with the members 15, as shown, or suitably welded to the members, the trough-shaped

member extending throughout the length of the support, terminating, however, short of where the sides taper as described. Adjustably secured to the support is a tray in the form of a plate member 20 having a contour such as to provide a rectangular foremost portion and a triangular rear portion, as more particularly shown in Figure 3. The plate at the front edges of the rectangular portion is provided with uprights 21 located on the respective sides of the longitudinal center of the plate, which uprights have associated therewith a spaced upright 22 formed integrally with a backing member 23 adjustably positioned on the plate.

For attaching plate member 20 to the support so that the same is adjustable with respect to the support the plate is provided with a central depressed portion 24 extending and forming a groove longitudinally of the plate. The plate and support are assembled with the recessed portion fitting within the member 17 and thus the parts 70 are retained in assembled relation, permitting the plate, however, to slide longitudinally on the support. A slot 25 is located in the depressed portion to the rear of the plate for receiving the securing screw 26 which passes through an opening in member 17 of the support and retained therein by the locking nut 27. The plate member has movement on the support to the extent permitted by the length of the slot 25 and by tightening the nut 27 the parts can be firmly secured 75

80 in desired position. The foremost portion of the groove 24 in the plate has located therein a metal bar 30 secured at its rear end to a support 31, the ends of which are welded to the edges of the groove, Figure 4, and at its other end to the bend 85 section 32 of the groove, which section is bent diagonally and then horizontally so that the bar is positioned with its entire upper surface substantially flush with the surface of the plate 20. The backing member 23 is provided with a rectangular slot in alignment with the bar so that a clip 33 secures the member to the bar, the clip 90 having U-formation and extending under the bar with its ends passing out of the slot and being 95 riveted to the upper surface of the member.

A slot 34, formed in the rear portion of the bar, receives a screw 35 threaded and extending upwardly from the clip 33 so that the movement of the backing member and upright 22 toward 105 and from the front uprights 21 is limited. The locking nut 36 on screw 35 can be tightened to retain the backing member in desired position so that the capacity of the tray can be adjusted 110 to suit conditions.

The supporting tray of the present invention is adjustable horizontally on the portion 17 of the horizontal support which is adjustable vertically on the standard 10 so that the desired position of the envelopes or cards held in upright position by the uprights 21 and 23 can be secured. Also the base 11 provides a receptacle for pins, clips and similar articles. If the typewriter desk is of the folding type and it is desired to close the same for the day or to use the desk for other purposes, it is only necessary to swing the support 14 to locate the tray out of the way or since the device is independent of the desk, the same can be lifted and placed to the rear of the desk.

It is to be understood that I do not wish to be limited by the exact embodiment of the device shown which is merely by way of illustration and not limitation, as various and other forms of the device will of course be apparent to those skilled in the art without departing from the spirit of the invention or the scope of the claims.

I claim:

1. A card and envelope support including a standard, a horizontal member positioned on the standard for vertical adjustment, a tray having a depending longitudinal rib for fitting in a groove formed in the member, securing means holding the member and tray in assembled relation, said tray having a slot receiving the securing means to make the same adjustable on the member, and a plurality of spaced uprights on the tray for retaining envelopes and the like.

2. A card and envelope support including a standard, a horizontal member positioned on the standard for vertical adjustment, a tray having a depending longitudinal rib for fitting in a groove formed in the member, securing means holding the member and tray in assembled relation, said tray having a slot receiving the securing means to make the same adjustable on the member, and a plurality of spaced uprights on the tray for retaining envelopes and the like, one of said uprights being movable toward and away from the other.

3. In a card and envelope support including a standard, a horizontal member forming a sup-

port adjustably positioned by said standard, said support having a trough formed in its upper surface, a tray having a formed portion to provide a depending rib on one surface and a groove in the other surface, said depending rib fitting in the trough to adjustably mount the tray on the support, uprights provided by the tray on the front edge thereof, a second upright adjustably secured to the tray, and means carried by the second upright for holding the same in adjusted position.

4. In a card and envelope support including a standard, a horizontal member adjustably positioned by said standard, said member having a trough formed in its upper surface, a plate member forming a tray having a formed portion to provide a depending longitudinal rib on one surface and a groove in the other surface, said depending rib fitting in the trough to adjustably mount the plate on the member, the front edge of said plate member having a portion bent upwardly to provide retaining means, an upright normally spaced from said retaining means, and means for adjustably securing the upright to the plate member including a bar secured to the plate member and disposed longitudinally of the groove therein, and a resilient clip carried by said upright.

5. In a card and envelope support including a standard, a horizontal member adjustably positioned by said standard, said member having a trough formed in its upper surface, a plate member forming a tray having a formed portion to provide a depending longitudinal rib on one surface and a groove in the other surface, said depending rib fitting in the trough to adjustably mount the plate on the member, the front edge of said plate member having a portion bent upwardly to provide retaining means, an upright normally spaced from said retaining means, a bar carried by the plate member and disposed longitudinally in the groove therein, and a securing screw carried by the upright and extending through a slot provided longitudinally of the bar whereby said upright may be secured in adjusted positions on the plate member.
